UNITED STATES PATENT OFFICE.

ANNA JENNINGS DANIEL, OF ST. LOUIS, MISSOURI.

PRACTICE-KEYBOARD.

1,125,268.

Specification of Letters Patent.

Patented Jan. 19, 1915.

Application filed April 24, 1913. Serial No. 763,374.

To all whom it may concern:

Be it known that I, ANNA JENNINGS DANIEL, a citizen of the United States, residing at No. 1604 South Grand avenue, in the city of St. Louis, State of Missouri, have invented new and useful Improvements in Practice-Keyboards, of which the following is a specification.

My invention relates to practice keyboards and consists in the novel construction, combination, and arrangement of its parts as illustrated in the accompanying drawings, and hereinafter described, and the object of my invention, is to provide a practice keyboard as a means for noiseless practice of finger exercises and scales, at the same time affording the requisite training for sight and touch.

In the accompanying drawings: Figure 1, 20 is a transverse sectional view, Fig. 2, a top view of the same, showing hinge joint, Fig. 3, a detail sectional view of adjustable key-stop, and Fig. 4, a perspective view of the inner end hinged sections of skeleton frame-work and springs, of a practice keyboard, provided with my invention, the nature of which is defined in the claims hereinafter presented.

Similar reference numerals refer to like 30 parts in all views.

The white keys 1, and the black keys 2, for this device rest on flat metal springs 3, 4, respectively, Fig. 1, which project obliquely forward and upward; the lower ends 35 of the springs 3, 4, are fitted beneath a continuous metal strip 5, over metal strip 6, through all of which screws or bolts pass, 7, to secure the springs to the wood support 8, the springs being individually secured by a 40 pair of screws 9, 9, and at the required height, over the rear ends of the springs, the keys 1, 2, are pivotally mounted on the rod 10, and accurately spaced from each other by washers (not shown), each key 45 having a circular hole for the reception of rod 10, the rod 10, being supported at intervals by brackets 11, which take the place of washers where used, and are secured to the wood pieces 8, by screws 12; the wood pieces 50 8, 13, Figs. 1, 4, are made secure to hinge 28, with screws 32, at their inner ends, and to wood brackets at their outer ends, to prevent the black keys 2, from flying off the springs 4, when released; a strip 27, is likewise attached under the white keys to each 55 of the front uprights 29, and said uprights

29, are similarly attached at the forward edges of the keyboard; the guide posts 17, are mounted on strip 27, at proper intervals, entering apertures 16, in white keys as lateral guides; beneath the front edges of the white keys, a felt pad, 21, acts as a noiseless stop when the keys are depressed.

In the above mentioned particulars, my improved practice keyboard, is somewhat 65 like that described in Letters Patent No. 921,806, granted to me May the 18, 1909.

In carrying out my present invention in combination with the above, I have made extensions 18, at the lower front edges of 70 the white keys 1, Figs. 1, 2, which project slightly forward beneath similar backward projections 19, Figs. 1, 2, 4, at inner top edge of front upright piece 29, to keep the white keys level, and in position on the 75 springs 3, when the keyboard is folded, or handled; this backward projection 19, is padded beneath with felt 20, Fig. 1, 4, to serve as a bumper when the white keys are released, after being depressed on felt pad 80 21, which white keys 1, Fig. 1, are limited in their downward movement, by adjustable keystops 22, Figs. 1, 2, 4, which key-stop is a piece of metal having its top edge, or upper side, padded with felt 23, with zigzag 85 perforations in its wall side, 25, Fig. 3, through which it can be raised and lowered, by shifting to right, or left, up, or down, (to suit the strength of a child's fingers) on set screws 24, Figs. 1, 4, and made stationary at 90 horizontal notches in the angles, by thumb nuts 26, to front bottom piece 27.

In the lower forward ends of the black keys 2, I have made grooves 15, Fig. 1, in which the springs 4, being rigidly secured 95 beneath continuous metal strip 5, each individually by a pair of screws 9, to the wood support 8, and having their free ends curved slightly downward, slide forward, when the keys are depressed, to prevent the 100 same from moving laterally, or otherwise than up and down as intended; the back stop 13, is padded with felt 14, to act as noiseless stop to black keys when released, after being depressed; said black keys 2, 105 together with the white keys 1, are threaded by rod 10, Figs. 1, 4, the rod 10, being supported at intervals by metal brackets 11, Fig. 1, which are made fast to the wood support 8, with screw 12, and having circular hole near the top through which the rod 10, passes, and is thus secured at the 110

required height above the wood support 8. The hinge 28, Figs. 1, 4, is made with continuous rib 30, having upright extensions 31, at rear, secured to the wood pieces 8, 13, 27 and 29, with screws 32, and is provided with corner pockets 33, Fig. 4, at top to rear, and with right angled extensions 38, at bottom to rear, and in front, with similar projections 39, extending up and over the front uprights 29, while the white keys either side next hinge 28, are undercut to fit over the hinge metal, leaving the inner side of white keys flush with the hinge surface to admit of imperceptible break in the keyboard when in position, and the keys are depressed.

From the above description, it is obvious that with my improved construction, a practice keyboard is provided, of neat and finished appearance, which can be noiselessly and effectively used for practice purposes.

What I claim as new and desire to secure by Letters Patent is:

1. In a practice keyboard, a body frame; a supporting rod thereon; means on said body frame for holding said rod stationary above said body frame; a plurality of white and black keys pivotally mounted on said rod; a plurality of springs rigidly fastened at their lower ends on said body frame beneath the rear end portions of said keys, each individually with a pair of screws; a metal strip secured over the fastened end portions of said springs; said springs projecting forwardly and upwardly with uniform slant and strength, and having their free end portions curved slightly downward and slidably supporting said keys; means on said body frame for individually guiding the white keys and supporting them laterally; coöperating stops on the forward portions of said white keys and the adjacent portion of the body frame for limiting the upward movement of said keys; the black keys having longitudinal grooves in their under sides in which the forward end portions of the respective springs therefore are seated; and means on said body frame for limiting the upward movement of the black keys.

2. In a practice keyboard, a body frame; a supporting rod thereon; means on said frame for holding said rod stationary above said body frame; a plurality of white and black keys pivotally mounted on said rod; a plurality of springs rigidly fastened at their lower ends on said body frame beneath the rear end portions of said keys, each individually with a pair of screws; a metal strip secured over the fastened end portions of said springs; said springs projecting forwardly and upwardly with uniform slant and strength, and having their free end portions curved slightly downward and slidably supporting said keys; means on

said body frame for individually guiding the white keys and supporting them laterally; coöperating stops on the forward portions of said white keys and the adjacent portion of the body frame for limiting the upward movement of said keys, and intervening felt pads; the black keys having longitudinal grooves in their under sides in which the forward end portions of the respective springs therefore are seated; means on the said body frame for limiting the upward movement of the black keys, and intervening felt pads; and means for limiting the downward stroke of the white keys, said means comprising a vertically adjustable horizontal strip, underlying the forward portions of said keys.

3. A keyboard of the character described, comprising a plurality of pivoted keys; resilient means for supporting said keys in normal raised position; and means for limiting the downward stroke of the keys, said means comprising a vertically adjustable horizontal strip, underlying forward portions of the keys.

4. A keyboard of the character described, comprising a plurality of pivoted keys; resilient means for supporting said keys in normal raised position; and means for limiting the downward stroke of the keys, said means comprising a horizontal strip having like inclined slots at different places in its length, and supporting studs projecting through said slots, whereby an endwise movement of the strip on said studs effects a bodily vertical movement of the strip.

5. A keyboard of the character described, comprising a plurality of pivoted keys; resilient means for supporting said keys in normal raised position; and means for limiting the downward stroke of the keys, said means comprising a horizontal strip having like inclined slots at different places in its length, supporting studs projecting through said slots, whereby an endwise movement of the strip on said studs effects a bodily vertical movement of the strip, and means for fastening the strip in adjusted position.

6. A keyboard of the character described, comprising a plurality of pivoted keys; resilient means for supporting said keys in normal raised position; and means for limiting the downward stroke of the keys, said means comprising a horizontal strip having like zig-zag slots at different places in its length, said slots having horizontal notches in the angles thereof, supporting studs projecting through said slots, and means co-operating with said studs for fastening said strip in adjusted position.

7. A practice keyboard comprising a sectional body frame, the body frame sections each comprising spaced front and rear longitudinal members; a supporting rod above

the rear base member; means on rear base member for holding said rod stationary; a padded upper longitudinal frame member above said rod; an upstanding strip at the 5 front of said front base member, said upstanding strip having an inwardly projecting padded ledge; white and black keys hinged at their rear ends on said supporting rods, the white keys having shoulders 10 at their front ends projecting under said padded ledge on said upstanding front base strip, the black keys having shoulders at their rear inner ends adapted to abut against upper padded frame member; springs 15 rigidly secured on said rear base member and projecting forwardly and upwardly with substantially equal slant and strength, the free end of said springs being turned slightly downward and slidably engaging 20 the under sides of the keys; the black keys having longitudinal slots in which their respective springs rest; means on said front base member engaging the white keys for guiding and laterally supporting them; and 25 a hinge connecting the meeting ends of the frame sections, said hinge being secured to the inner ends of the longitudinal frame members and acting as a support and tie

therefor, the hinge having flange extensions engaging the side faces of the said frame 30 members.

8. In a practice keyboard of the character described, a sectional body frame; the body frame sections each comprising spaced front and rear longitudinal base members; an 35 upper longitudinal frame member above the rear base member; an upstanding longitudinal strip at the front of the front base member; a longitudinal supporting rod for the keys; and a hinge connecting the meeting 40 ends of said body frame sections, said hinge being secured to the inner ends of the respective longitudinal frame members, upstanding strips and key-supporting rods, and acting as a support and tie therefor; said 45 hinge having flange extensions engaging the faces of said frame members; and brackets placed at intervals, made fast to the rear base member, and having a circular hole 50 near the top, through which the key-supporting rod passes.

ANNA JENNINGS DANIEL.
